UNITED STATES PATENT OFFICE.

WILLIAM MAYER AND CHARLES S. LEVY, OF SAN FRANCISCO, CALIFORNIA.

CONDIMENT-HOLDER.

1,172,155.

Specification of Letters Patent.

Patented Feb. 15, 1916.

Application filed December 12, 1914. Serial No. 876,900.

To all whom it may concern:

Be it known that we, WILLIAM MAYER and CHARLES S. LEVY, citizens of the United States, residing at San Francisco, in the county of San Francisco and State of California, have invented new and useful Improvements in Condiment-Holders, of which the following is a specification.

This invention relates to condiment holders of that class which are adapted to dispense two different condiments, such as salt and pepper.

The invention has for its object to produce a device of this class comprising a receptacle having a partition wall whereby it is divided into two compartments in combination with a cover having distributing apertures and provided with a simple and effective valve mechanism, whereby the distributing apertures are normally obstructed, but which may be readily manipulated so as to uncover the distributing apertures communicating with one or the other compartment.

A further object of the invention is to produce a device of the class described provided with a guard washer to form an extended supporting and bearing surface for the valve mechanism.

With these and other ends in view which will readily appear as the nature of the invention is better understood, the same consists in the improved construction and novel arrangement and combination of parts which will be hereinafter fully described and particularly pointed out in the claims.

In the accompanying drawing has been illustrated a simple and preferred form of the invention, it being, however, understood that no limitation is necessarily made to the precise structural details therein exhibited, but that changes, alterations and modifications within the scope of the claims may be resorted to when desired.

In the drawing,—Figure 1 is a perspective view of the cap of the improved condiment holder with parts broken away to expose the underlying construction. Fig. 2 is a plan view showing the cap detached and inverted. Fig. 3 is a front view of the condiment holder with the cap attached and with parts broken away. Fig. 4 is a top plan view of the device. Fig. 5 is a transverse sectional view taken on the line 5—5 in Fig. 4. Fig. 6 is a horizontal sectional view taken on the line 6—6 in Fig. 5. Fig.

7 is a sectional detail view taken on the line 7—7 in Fig. 6.

Corresponding parts in the several figures are denoted by like characters of reference.

The improved device consists of a receptacle 10 of glass or other material having a transverse partition wall 11 whereby compartments 12, 13 are formed for the reception of two condiments, such as salt and pepper. The upper end of the receptacle is externally threaded, as at 14, for the reception of a correspondingly threaded cap 15 made preferably of metal, and the top of which is provided with different sized apertures 16, 17 adapted to communicate with the compartments 12 and 13, respectively. For the purpose of normally obstructing these apertures two approximately semi-circular valve members 18, 19 are provided, said valve members being positioned at opposite sides of a brace bar 20 which is secured on the under face of the apertured top portion of the cap. Each of the valve members is provided with a pivot lug 21, said pivot lugs projecting into a recess 22 in the brace bar, where said lugs are superposed in pivotal engagement with one of the rivets 23, whereby the brace bar is secured in position. The brace bar has a second recess 24 at the front end thereof for the accommodation of an arm or lever 25 which pivotally engages a second rivet 26, whereby the brace bar is secured in position. The arm or lever 25 is provided with a handle 27 that extends through a slot 28 in the forward portion of the cap.

The valve members 18, 19 are peripherally grooved, as seen at 28, for the accommodation of the end portions of an arcuate spring 29 that extends through the rearward portion of the brace bar 20, the tension of said spring being exerted against the outer edges of the valve members, both of which will thereby be forced normally in the direction 100 of the brace bar in which position the sifting apertures 16 and 17 will be obstructed. The valve members 18, 19 are provided, respectively with different sized apertures 30, 31 which, when said valve members are 105 forced outward against the tension of the actuating spring may be placed in registry with the apertures 16, 17, respectively. Such outward movement of either valve member may be accomplished by pressure 110 thereagainst of the lever 25. The latter is provided with a recess 32 wherein lugs or

tongues 33 projecting from the respective valve members near their forward ends are guided. Similar lugs or tongues 34 near the rear ends of the respective valve members are guided in the recess 35 in the brace bar.

Fitted in the cap 15 directly below the brace bar, lever and valve members is a washer 36 having openings 37, 38 communicating with the compartments 12, 13, respectively, when the cap is applied in position for use, it being obvious that the engaging threads of the cap and the receptacle must be of such extent that the cap will be seated when the openings 37, 38 communicate with the compartments 12, 13, and it being, furthermore, obvious that the said openings 37, 38 must be in registry with the respective valve members. The openings 37, 38 are separated by a bridge piece 39 which will engage the top edge of the partition member 11. Thus, when the cap is seated, there will be no danger of the contents of the two compartments getting mixed.

It will be seen that when the holder or receptacle is charged with condiments and the cap or cover is placed in position, the shifting apertures will normally be obstructed. By pressing the handle of the lever 25 in one direction or the other, and at the same time inverting and shaking the device the contents of either compartment will be permitted to sift out. As soon as the handle of the lever is released, the valve member or members will be restored to obstructing position.

It is desired to note that the parts are to be so arranged that in order to actuate the obstructing valve associated with the salt compartment, the lever will be pressed in the direction in which the cap is turned to tighten it upon the receptacle. Thus, whenever salt is used, the tendency will be to tighten the cap. Inasmuch, as salt is used much more frequently than pepper it is obvious that this arrangement will tend to maintain the cap normally in a tightly seated position.

For the purpose of assisting in preventing the cap from being dislodged or unscrewed by the exertion of moderate pressure on the lever handle, there is formed in the threaded portion of the cap an indentation producing on the inner face a bulb or projection 42; the threaded portion of the receptacle is provided with a notch 43 forming a seat for said bulb. The notch and the bulb must obviously be so disposed as to engage with one another when the cap is screwed down to its seated position. The resiliency of the metal of which the cap is preferably composed will permit the bulb to ride over the screw threads of the receptacle while the cap is being applied. When the cap reaches its seat the bulb will drop into the notch and,

while not preventing the unscrewing of the cap by the exercise of due force, it will largely tend to prevent the accidental dislodgment of the cap.

Having thus described the invention, what is claimed as new, is:

1. A condiment holder having two compartments, in combination with a top or cap having sifting apertures, spring-actuated valve members normally obstructing the sifting apertures and having apertures which may be placed in registry therewith, and a lever whereby either valve member may be displaced against the tension of its actuating spring while the other valve member remains in its obstructing position.

2. In a two-compartment condiment holder, a sifting top consisting of a cap having apertures, a brace bar engaging the under face of the top portion of said cap, said brace bar having recesses, approximately semi-circular valve members having lugs engaging one of said recesses, a lever engaging the other recess and having a handle projecting through the wall of the cap, said wall being slotted for the passage thereof, a rivet extending through the brace bar and through the lugs of the semi-circular valve members, said rivet constituting a pivot member for said lugs, and a second rivet extending through the brace bar and through the lever, said rivet constituting a fulcrum for the lever, said valve members being provided with apertures adapted to register with the sifting apertures in the cap.

3. In a two-compartment condiment holder, a sifting top consisting of a cap having apertures, a brace bar engaging the under face of the top portion of said cap, said brace bar having recesses, approximately semi-circular valve members having lugs engaging one of said recesses, a lever engaging the other recess and having a handle projecting through the wall of the cap, said wall being slotted for the passage thereof, a rivet extending through the brace bar and through the lugs of the semi-circular valve members, said rivet constituting a pivot member for said lugs, and a second rivet extending through the brace bar and through the lever, said rivet constituting a fulcrum for the lever, said valve members being provided with apertures adapted to register with the sifting apertures in the cap; and an arcuate spring extending through the brace bar and engaging the peripheral portions of the valve members, the latter being grooved for the reception of the end portions of said spring.

4. In a two-compartment condiment holder, a receptacle having a transverse partition, a sifting cap having apertures communicating with the compartments at the opposite sides of the partition, spring-actu-

ated valve members normally obstructing the sifting apertures in the cap, said valve members being provided with apertures which may be brought in registry with the 5 sifting apertures when said valve members are displaced against the tension of the actuating spring, and a lever whereby said valve members may be actuated, said cap being provided with a washer or diaphragm 10 having openings alining with the valve

members and communicating with the compartments of the holder.

In testimony whereof we affix our signatures in presence of two witnesses.
